FREEZE DRYER

Douglas S. Fraser, New Paltz, N.Y., assignor to
FTS Systems, Inc., Stone Ridge, N.Y.

Filed July 29, 1974, Ser. No. 492,887

Term of patent 14 years

Int. Cl. D24—01

U.S. Cl. D32—2 C

F-1-2-

F-1-1-

F-1-3-

FIG. 5

FIG. 4

FIG. 1 is a front perspective view of a freeze dryer showing my new design;

FIG. 2 is a right side elevational view of the freeze dryer shown in FIG. 1;

FIG. 3 is a front elevational view of the freeze dryer shown in FIG. 1;

FIG. 4 is a rear elevational view of the freeze dryer of FIG. 1; and

FIG. 5 is a left side elevational view of the freeze dryer of FIG. 1.

I claim:

The ornamental design for a freeze dryer, as shown.
